LUGGAGE HOLDER

Julius Ritter, Jr., Racine, Wis., assignor to Hartmann Trunk Company, Racine, Wis., a corporation of Wisconsin

Application December 17, 1930, Serial No. 502,943

4 Claims. (Cl. 190—41)

The present invention relates in general to improvements in the construction of luggage carriers, and relates more specifically to an improved tray structure especially applicable to suitcases, trunks or other luggage housings, for the purpose of confining wearing apparel or garments therein.

A general object of the invention is to provide an improved luggage confining structure which is simple and compact in construction, and which is moreover highly efficient in use.

The present tendency towards increase in air travel makes it imperative for the manufacturers of trunks and hand luggage for such transportation to reduce to a minimum the size and weight of their products, without undesirably sacrificing available space. The traveling public also demands that containers for wearing apparel such as suits and overcoats, be adapted to effectively conceal such garments without undesirably crushing and wrinkling the same, and that the garments be readily accessible without necessarily disturbing other paraphernalia confined within the carrying case. While it is desirable to have such garments thus snugly and safely confined within the luggage carrier during transportation, it is also frequently desirable to remove the articles and to hang the same up in a wardrobe or closet when the destination of the traveler has been reached, and it frequently happens that no proper garment hanging facilities are available at such destination.

It is a more specific object of the present invention to provide an improved luggage carrier which meets all of the special requirements for every class of transportation, and for the traveling trade in general.

Another specific object of the invention is to provide an improved garment confining tray which is especially adapted for the reception and effective housing of wearing apparel such as suits, coats, dresses, or the like.

A further specific object of the invention is to provide an improved luggage housing structure which will confine a maximum quantity of paraphernalia in minimum space, and wherein certain wearing apparel is segregated from other miscellaneous luggage.

Still another specific object of the invention is to provide conveniently accessible and manipulable means for confining articles such as men's suits, during transportation thereof, without undesirably crushing the garments.

Another specific object of the invention is to provide an improved coat hanger which occu-

pies minimum space, and which is moreover adapted either for snug confinement within a carrier case, or for effective use when hanging an associated garment in a wardrobe or closet.

These and other specific objects and advantages will be apparent from the following detailed description.

A clear conception of an embodiment of the invention showing the same specifically applied to an ordinary suitcase, may be had by referring to the drawings accompanying and forming a part of this specification in which like reference characters designate the same or similar parts in the various views.

Fig. 1 is a top view of an open suitcase showing one of the improved tray structures applied therein with the trousers of a man's suit in place;

Fig. 2 is a similar view of the open suitcase and tray, showing the trousers applied and a coat about to be applied, to the tray;

Fig. 3 is a similar view of the open suitcase showing several trays therein, a complete suit having been applied to the upper tray which has also been slightly displaced in order to expose a portion of the tray directly beneath;

Fig. 4 is a transverse vertical section through the suitcase showing two empty superimposed garment confining trays therein;

Fig. 5 is a similar vertical section through the suitcase and trays, showing garments completely applied to the lower tray and further showing garments partially to the upper tray;

Fig. 6 is also a similar section through the suitcase and trays, showing both trays loaded and the upper of the trays about to be folded into the cover section of the case;

Fig. 7 is a top view of one of the improved trays in empty condition and removed from the confining housing;

Fig. 8 is a front view of the improved tray looking toward the longitudinal edge thereof;

Fig. 9 is a vertical section through the improved tray, taken along the line 9—9 of Fig. 7 and looking in the direction of the arrows;

Fig. 10 is a front elevation of an improved coat hanger especially adapted for use in conjunction with the improved tray structure;

Fig. 11 is a side elevation of the improved coat hanger, showing the supporting hook thereof in one position of adjustment; and

Fig. 12 is a side elevation of the coat hanger with the supporting hook shown in another position of adjustment.

While the improved garment holding tray structure will be hereinafter described as being

applied to an ordinary suitcase, it should be understood that it is not intended to thereby limit the scope of the invention since some of the novel features are obviously more generally applicable.

5 Referring to the drawings, the suitcase comprises a main section 14, a cover section 15 swingably connected to the section 14 by means of a hinge, and side straps 16 for limiting the swinging movement of the cover section 15. The main 10 section 14 may be provided with partitions 17, and a lower tray 18 is formed for confinement within the section 14 directly adjacent to the partitions, the opposite ends of the tray 18 being cooperable directly with parallel supporting strips 15 19 secured to the main section end walls. A second or upper tray 20 is formed for confinement within the cover section 15, by means of snap fasteners 21, 22 of which the fasteners 21 serve as detachable hinges disposed near the case 20 section hinge. When the suitcase is open, the lower tray 18 rests upon the strips 19 above the partitions 17, and the upper tray 20 may be swung downwardly over the tray 18 upon release of the fastener 22. Upon further release of the hinge 25 fasteners 21, the upper tray 20 may also be freely removed from the suitcase, and the lower tray 18 may be lifted freely from within the main section 14. Since the tray structures are identical, except for their supporting and retaining means, it is only necessary to describe one of these trays 18, 20 in detail.

Referring to Figs. 7, 8 and 9 it will be noted that the upper tray 20 comprises a supporting plate 23 having integral end walls 24; a pair 35 of laterally spaced flaps 25 pivotally attached to the plate 23 near one of the longitudinal edges thereof; and a retainer bar 26 detachably associated with the side walls 24 near the opposite longitudinal edge of the plate 23. The plate 40 23 may be formed of any light and strong material such as veneered wood or fibre board, and the flaps 25 may be formed of relatively flexible material sewed or otherwise hingedly attached to the plate 23 near its edge. The forward ends 45 of the flaps 25 are adapted to extend beneath the cross bar 26, and this bar is detachably confined within the notches 27 at the upper edges of the end or side walls 24, by means of snap fasteners 28.

50 Secured to the tray plate 23 between the flaps 25, is a pocket 29 formed of leather or other suitable material, and this pocket is open toward the adjacent edge of the plate 23 for the reception of a clothes-hanger hook 30. The hanger hook 30 is pivotally associated with the hanger 55 31 formed of wood or the like, and may be adjusted to either of the two positions shown in Figs. 10, 11 and 12. When the hook 30 is disposed as shown in full lines in Figs. 10 and 11, the hanger 60 31 may be utilized to support garments in the usual manner from a wall hook, rod or the like. When in the position shown in dash-lines in Fig. 10 and in full lines in Fig. 12, the hook 30 is capable of being slipped into a pocket 29 of one 65 of the trays 18, 20, thus positioning the hanger 31 parallel to and above the adjacent tray plate 23, and as near to the adjacent plate edge, as possible.

70 During normal use of the improved trays 18, 20, and assuming the trays to have been applied to a suitcase as shown in Figs. 1 to 6 inclusive, the lower tray 18 may be positioned upon its supporting strips 19 and the upper tray 20 swung downwardly thereover as in Fig. 1. By manipulating the flaps 25 with the retainer bar 26 re-

80 moved, a pair of trousers 32 may be applied to the upper tray 20, as shown in Fig. 1, in an obvious manner. After the trousers 32 have been thus applied and folded, a coat 33 associated with a hanger 31 may be next applied to the tray 20, as shown in Fig. 2, with the hanger hook 30 inserted into the adjacent pocket 29. The cross bar 26 may then be fastened in place by means of the snap fasteners 28, and it should be noted that when the coat 33 is thus positioned upon a tray, the lapels and collar thereof lie substantially within the space between the two flaps 25, thereby protecting these portions of the coat 33 against undesirable crushing. The lower portions of the coat 33 and of the sleeves thereof, may subsequently be folded over the retainer bar 26 as shown in Fig. 3, thereby completing the loading of the tray 20 preparatory to concealment thereof within the suitcase. If it is also desired to pack a vest with the trousers 32 and coat 33, the vest may be placed either between the trousers 32 and the tray plate 23, or over the hanger 31 within the coat 33. The garments when thus carefully applied, are obviously well protected against subsequent crushing and wrinkling.

85 90 95 100 After the tray 20 has been thus loaded, it may either be swung into the cover section 15 about the hinge fasteners 21 as shown in Fig. 6, or removed from the case as shown in Fig. 3 after releasing the fasteners 21. When the loaded tray 105 20 is positioned within the cover section 15 or removed, the lower tray 18 is freely accessible for loading or removal, thereby permitting convenient access to all portions of the suitcase. While more than two trays 18, 20 may be readily confined within a single suitcase, the ordinary traveling requirements do not necessitate such increase in trays, and the trays 18, 20 may obviously be utilized to support garments other than trousers 32 and coats 33 such as shown.

110 115 120 125 130 From the foregoing description, it will be apparent that the invention provides simple, compact, and readily accessible means for confining garments within a housing, without crushing the same. The improved tray structure besides being light and strong, may be applied to various types of housings and is readily removable so as to permit convenient access to other portions of the housing. The structure has proven highly successful in commercial use, especially as applied to a standard suitcase such as illustrated herein.

135 140 145 150 It should be understood that it is not desired to limit the invention to the exact details of construction herein shown and described, for various modifications within the scope of the claims may occur to persons skilled in the art.

It is claimed and desired to secure by Letters Patent:

1. A garment carrier tray comprising, a supporting plate, a pair of laterally spaced flaps pivotally connected to one edge portion of said plate and swingable across the tray so as to permit substantially one-half of a garment to be confined between the flaps and plate and the other half to fold over one flap and to extend beneath the other by virtue of the lateral spacing thereof, and a retainer bar extending over the swinging ends of said flaps beyond the zone of folding, said bar being removable in order to permit swinging of said flaps for loading and unloading purposes.

2. A garment carrier tray comprising, a supporting plate, a pair of laterally spaced flaps pivotally connected to one edge portion of said plate

- and swingable across the tray so as to permit substantially one-half of a garment to be confined between the flaps and plate and the other half to fold over one flap and to extend beneath the other by virtue of the lateral spacing thereof, a retainer bar extending over the swinging ends of said flaps beyond the zone of folding, said bar being removable in order to permit swinging of said flaps for loading and unloading purposes, and a garment hanger secured to said edge portion of said plate oppositely of said bar and between said flaps so as to permit the medial portion of a garment carried by said hanger to be folded around said bar. 5
- 10 3. A garment carrier tray for suit cases, comprising, a supporting plate having opposite end walls, a pair of laterally spaced flaps pivotally connected to one edge portion of said plate between said walls and swingable across the tray so as to permit substantially one half of a garment to be confined between the flaps and plate and the other half to fold over one flap and to extend beneath the other by virtue of the lateral spacing thereof, a retainer bar coacting directly with said end walls and extending over the swinging ends of said flaps beyond the zone of folding, said bar being removable from said walls in order to permit swinging of said flaps for loading and unloading purposes, a garment hanger secured to said edge portion of said plate oppositely of said bar and between said flaps and said walls so as to permit the medial portion of a garment carried by said hanger to be folded around said bar, and means for detachably pivotally connecting said edge portion of the tray within the suit case near the hinge of the latter. 15
- 20 4. A garment carrier tray for suit cases, comprising, a supporting plate having opposite end walls, a pair of laterally spaced flaps pivotally connected to one edge portion of said plate between said walls and swingable across the tray so as to permit substantially one half of a garment to be confined between the flaps and plate and the other half to fold over one flap and to extend beneath the other by virtue of the lateral spacing thereof, a retainer bar coacting directly with said end walls and extending over the swinging ends of said flaps beyond the zone of folding, said bar being removable from said walls in order to permit swinging of said flaps for loading and unloading purposes, a garment hanger secured to said edge portion of said plate oppositely of said bar and between said flaps and said walls so as to permit the medial portion of a garment carried by said hanger to be folded around said bar, and means for detachably pivotally connecting said edge portion of the tray within the suit case near the hinge of the latter. 25
- 25 3. A garment carrier tray for suit cases, comprising, a supporting plate having opposite end walls, a pair of laterally spaced flaps pivotally connected to one edge portion of said plate between said walls and swingable across the tray so as to permit substantially one half of a garment to be confined between the flaps and plate and the other half to fold over one flap and to extend beneath the other by virtue of the lateral spacing thereof, a retainer bar coacting directly with said end walls and extending over the swinging ends of said flaps beyond the zone of folding, said bar being removable from said walls in order to permit swinging of said flaps for loading
